UNITED STATES PATENT OFFICE.

MICHEL G. FAGAN, OF TROY, NEW YORK.

HYDROCARBON-VAPOR STOVE.

SPECIFICATION forming part of Letters Patent No. 341,739, dated May 11, 1886.

Application filed June 9, 1884. Serial No. 134,265. (No model.)

To all whom it may concern:

Be it known that I, MICHEL G. FAGAN, of the city of Troy, county of Rensselaer, State of New York, have invented a new and useful

5 Improvement in Hydrocarbon-Vapor Stoves, of which the following is a specification.

My invention relates to hydrocarbon-vapor-burning stoves, and more particularly to certain improvements upon the apparatus belonging to that class of them with which an 10 air-forcing mechanism is connected, and for which Letters Patent were granted to me January 17, 1882, No. 252,307.

One of the objects of my improvement herein to be described and illustrated is to divide the current of air coming from the forcing mechanism, so as to direct a part of it through the hydrocarbon-evaporating vessel, and to cause another portion of the said air under 15 impetus to mix with the charged air coming from the evaporating-vessel before it reaches the burners, so as to more perfectly consume the same. When the evaporating-vessel is nearly full of hydrocarbon liquid, the air becomes so heavily charged with combustible 20 vapor, if the whole pressure-current of air is under its influence, that it is liable to evolve smoke while burning, and by mixing air with it before it reaches the burners this contingency 25 is avoided.

Another object of my invention is to combine with a hydrocarbon-vapor-burning stove an oven and warming-closet, and also a means to burn a part of the hydrocarbon vapor produced by the apparatus connected with the 30 stove for purposes of illumination, that the cooking operations being carried on may be seen when the stove is being used at night, the details of which, in construction and arrangement, will be fully given and explained 35 hereinafter.

Accompanying this specification, to form a part of it, there are two plates of drawings containing four figures illustrating my invention, with the same designation of its parts by 40 letters of reference used in all of them.

Of these illustrations, Figure 1 shows a side elevation of a hydrocarbon-vapor-burning stove containing my invention and improvement. Fig. 2 shows a longitudinal central 45 vertical section of the same stove. Fig. 3 illustrates a perspective of the evaporating-

vessel, and Fig. 4 shows in an enlarged proportion a valve and a branch pipe in part that are used to divide and regulate the entering 55 current of air and its distribution.

The several parts of the stove are designated by letter-reference, and the function of the parts is described as follows: The letter S indicates the stove sides, T its boiler-hole top, 60 and e its bottom. The letter B designates an evaporating-vessel for containing hydrocarbon liquid, said vessel being made with labyrinthian passages or flues t, formed by partitions F, and the letters a indicate wicks suspended 65 in said flues to facilitate and increase the evaporation of the hydrocarbon liquid, the said hydrocarbon vessel thus shown being the same in construction that is illustrated in my patent before alluded to.

The letter P indicates an inclosure containing a mechanism for injecting air by means of clock-work and a fan into one of the outer flues of the evaporating-vessel by and through an offset or tube, p^x, connecting the center 70 flue with the air-supply pipe p', and p^z designates a pipe leading from the central flue of the evaporating-vessel, to convey away to be burned the mixed air and hydrocarbon vapor.

The letter p^y indicates a pipe that connects 75 with the air-conveying pipe p', and the vapor and air conveying pipe p^z, and V' indicates a valve placed on the pipe p^y, which, when open, permits air under pressure to pass to the pipe p^z and mix with the combined air and vapor 80 coming from the evaporating-vessel, and so that when the vapor is too dense to burn without smoking, air may be mixed with it to prevent this difficulty.

The letters p⁴ and p⁵ indicate branch pipes, 85 which connect with the pipe p^z, and supply flame to the under side of the boiler-hole top openings, O O, and p⁶ a pipe for conveying the combustible vapor to the water-reservoir R, the pipes p⁴ p⁵ p⁶ all connecting with the pipe 90 p^z, from which they receive a supply of hydrocarbon vapor.

The letter d designates a pipe leading from the pipe p^z, to convey a part of the vapor to be burned beneath the oven N, and the letter 100 J indicates a pipe connecting with the central chamber or flue of the evaporating-vessel B, which pipe is provided with burners for the ignition and burning of the vapor for illumin-

nating the surroundings of the stove when the latter is used at night or in a dark place, so that the operations of cooking may be observed.

5 The top T and bottom e are arranged in about the same manner herein as the same parts are shown in the stove illustrated in the patent alluded to, and to this structure I have added an oven, N, made with a top flue, F², 10 side flues, F' F', and a bottom flue, E, constructed with ingress air-openings n at the front, for the admission of air to the said bottom flue, E.

15 The letter V² designates a valve on the pipe leading to the oven, and V³ and V⁴ valves on the pipe leading to the boiler-hole openings O, located in the top of the stove.

20 The letter V⁵ indicates a valve on the pipe for supplying hydrocarbon vapor to the reservoir R, and as these valves V² V³ V⁴ V⁵ are arranged in the pipes the reservoir or either of the boiler-hole top openings may be used separately from the others, or all of them may be used together, or a part of them used together. 25 The reservoir R is combined with a bottom flue and a side flue and exit-opening, the latter being designated at m' and the former at m².

30 I am aware that for heating soldering-irons there has been used "a close vessel or reservoir to contain air under pressure," which was connected by means of a pipe with a carbon vaporizer, and that the mixture of air and carbonized vapor passing from the latter to burn was supplied by a current of air coming from an air-blast, with the latter produced by a mechanical means that was separate from that which forced the air into the close vessel or reservoir. This older means differed from 35 mine in the fact that in the latter but one means of giving motion or pressure to the air is employed, and the moving current of air when passing through a conduit is divided before entering the hydrocarbon vaporizing-vessel, one portion of the current being conducted by a pipe to the latter and the other current through a pipe to mix with the carbonized air, with an intermediate valve on the latter pipe to regulate the amount of passing air.

40 For a mechanism to supply air under pressure any of the well-known means employed for that purpose may be used, that which I

prefer to employ being actuated by a weight and clock-work which operates a fan.

45 Having thus described my invention, what I claim, and desire to secure by Letters Patent, is—

1. The stove herein described, provided with the chamber P, having mounted therein an air-forcing mechanism to produce a current of air therefrom, and provided with an air-conduit pipe, p' p^x p³, having a valve, v', in combination with the hydrocarbon chamber B, provided with a conduit-pipe, p², provided with a burner at its delivery end, and arranged to intersect the open end of the air-pipe p³, substantially as described, and for the purpose stated.

2. In a vapor-stove, the combination of the air-chamber P, having mounted therein an air-forcing mechanism for producing a current of air, and provided with the conduit-pipe p' p^x p³, having a valve, v', and arranged with its exit end to open in the hydrocarbon-conduit pipe, and the vaporizing-chamber B, having a hydrocarbon-conduit pipe intersecting the end of the air-conduit pipe, with the pipe d, provided with a burner at its delivery end, and having valve v², and arranged with its entrance end to intersect the hydrocarbon pipe, and opposite to the exit end of the air-pipe, substantially as described, and for the purpose stated.

3. In combination with the air-chamber P, having mounted therein an air-forcing mechanism for producing a current of air therefrom, and provided with the conduit-pipe p' p^x p³, having a valve, v', and arranged with its exit end to open into the hydrocarbon-conduit pipe, and the hydrocarbon-chamber B, provided with the pipe p², leading therefrom and intersected by the open end of the pipe p³, of the pipe p⁶, arranged on the upper end of the pipe p², and provided with a burner at its delivery end, substantially as described, and for the purpose stated.

Signed at Troy, New York, this 28th day of May, 1884, and in the presence of the two witnesses whose names were by them hereto written.

MICHEL G. FAGAN.
